UNITED STATES PATENT OFFICE.

THOMAS GASKINS, OF ARCADIA, FLORIDA.

PAPER-SERVING APPARATUS.

SPECIFICATION forming part of Letters Patent No. 510,782, dated December 12, 1893.

Application filed March 20, 1893. Serial No. 466,889. (No model.)

To all whom it may concern:

Be it known that I, THOMAS GASKINS, a citizen of the United States, residing at Arcadia, in the county of De Soto and State of Florida, have invented certain new and useful Improvements in Paper-Serving Apparatus; and I do declare the following to be a full, clear, and exact description of the invention, such as will enable others skilled in the art to which it appertains to make and use the same.

My invention relates to improvements in paper serving apparatus, and it has for one of its objects to provide such an apparatus embodying means whereby the paper may be quickly and conveniently cut across its entire width or any fraction thereof, and means whereby the paper may be as conveniently cut in the direction of its length at any point in its width.

Another object of the invention is to provide a serving apparatus, adapted, with slight adjustment, to mount rolls of paper of various lengths.

With the foregoing ends in view, the invention will be fully understood from the following description and claims when taken in connection with the annexed drawings, in which—

Figure 1, is a front elevation of my improved apparatus. Fig. 2, is a right hand end elevation of the same. Fig. 3, is a vertical transverse section taken in the plane indicated by the line *x*, *x*, of Fig. 1; and Figs. 4, 5, 6, and 7, are detail perspective views of several of the parts.

In the said drawings similar letters designate corresponding parts throughout the several views, referring to which—

A, indicates the main frame of the apparatus which comprises a base *B*, standards or uprights *C*, *C'*, and a cap bar *D*; and *E*, indicates a roll of paper which has its shaft or axis *a*, journaled in suitable bearings in the standards or uprights as shown. The standards or uprights *C*, *C'*, are respectively provided at their upper and lower ends with angular branches *b*, *b'*, and the branches *b*, of the standard *C*, are fixedly connected by screws as *c*, to the base *B*, and cap bar *D*, but the branches *b'*, of the standard *C'*, are provided with apertures for the passage of the shanks *d*, of the dovetail runners *e*, which runners are arranged in dovetail grooves *f*,

formed in the base and cap bar, as shown. The said runners *e*, are designed to permit the standard or upright *C'*, to be adjusted toward and from the standard *C*, so as to adapt the machine to mount rolls of paper of various lengths; and the said standard *C'*, is fixed in its various adjusted positions by means of the thumb nuts *h*, which are mounted upon the shanks of the runners *e*, as shown.

F, indicates the knife or knife bar through the medium of which the paper is cut in the direction of its width. This knife or knife bar *F*, is fixedly connected at one end to an arm *G*, which is pivotally connected to the standard or upright *C*; and in its inner side adjacent to its opposite end the said knife or knife-bar *F*, is provided with a dovetail groove *i*, which is designed to receive the dovetail projection *j*, at the end of the arm *H*, which arm is pivotally connected to the standard *C'*. By this manner of connecting the knife or knife bar *F*, it will be seen that it is free to swing inwardly so as to bear against the paper roll as the diameter of the same is reduced; and it will also be seen that the connection of the knife or knife bar will not interfere with the adjustment of the standard *C'*, since the projection *j*, will slide in the groove *i*, as the said standard is moved toward or from the standard *C*.

As better shown in Figs. 2, and 3, of the drawings, the knife or knife bar *F*, is provided upon its outer side with a longitudinal rib *I*, of dovetail form in cross section. This rib *I*, is designed to engage the dovetail groove *L*, in a slideable block *K*, which block is preferably provided with a lug as *m*, for the pivotal connection of the depending knife or knife bar *M*. By reason of this construction it will be readily noticed that the knife or knife bar *M*, may be moved to any point in the width of the paper and it will also be noticed that through the medium of said knife or knife bar, the paper may be conveniently cut in the direction of its length; it being simply necessary for the operator to press the knife or knife bar against the paper roll and pull the paper downwardly in the manner shown in Fig. 1.

The construction illustrated for connecting the slideable block *K*, to the knife or knife bar *F*, is preferable, but it is obvious that in some

cases the groove and rib might be of a different form in cross section and the groove might be formed in the knife bar and the rib upon the block to effect the same purpose.

5 In the practical operation of the invention, when it is desired to mount a roll of paper in the main frame, the standard C', is loosened and the shaft or axis of the roll is first placed in the bearing of the standard C, after which 10 it is placed in the bearing of the standard C', and said standard is moved toward the standard C, and fixed so as to prevent a casual displacement of the shaft or axis. When it is desired to cut the paper across its entire width, 15 the knife or knife bar M, may be swung upwardly out of the way or said knife or knife bar may be entirely removed from the knife or knife bar F, so as to enable the operator to draw the paper against the edge of said 20 knife, F, throughout the width of the paper. When it is desired to cut a piece of paper of less width than the web on the roll, it is simply necessary to adjust the knife or knife bar M, to the desired point and hold it against 25 the paper roll, when the paper may be cut transversely on the knife F, and longitudinally or in the direction of its length on the knife M, in the manner illustrated in Fig. 1.

From the foregoing description taken in 30 connection with the drawings, it will be seen that my apparatus is very simple, durable and inexpensive; and it will also be seen that through the medium of the same, pieces of paper of the exact size desired may be quickly 35 and conveniently cut, and thus the waste caused by roughly tearing the paper may be prevented, which is a desideratum.

I have specifically described the combination and relative arrangement of the several 40 elements of my improved apparatus, in order to impart a full, clear and exact understanding of the same, but I do not desire to be understood as confining myself to such exact construction and arrangement as such changes 45 or modifications may be made, in practice, as fairly fall within the scope of the invention.

Having described my invention, what I claim is—

1. In a paper serving apparatus, a frame 50 comprising a base having a groove in its upper or inner side, a cap bar having a groove in its lower or inner side, a standard or upright connected to the base and cap bar, the standard or upright C', having angular branches at its upper and lower ends, runners arranged in the grooves of the base and cap bar and having threaded shanks passed through the branches of said standard or upright and thumbnuts mounted on said threaded shanks, substantially as and for the purpose set forth.

2. In a paper serving apparatus, the combination with a frame comprising standards or uprights, one of which is adjustable; of a

knife having a groove, an arm connected to 65 the knife at one end and connected at its opposite end to one of the standards or uprights, and an arm connected at one end to the other standard or upright and having a projection at its opposite end engaging the groove of the 70 knife, substantially as and for the purpose set forth.

3. In a paper serving apparatus, the combination with a frame adapted to mount or support a roll of paper; of a knife extending in 75 the direction of the length of the frame, and a second knife disposed at an angle to the first named knife; the said knives being adapted to cut the paper in the direction of its width and in the direction of its length respectively, substantially as specified.

4. In a paper serving apparatus, the combination with a frame adapted to mount or support a roll of paper, and a knife extending in 85 the direction of the length of the frame and the paper roll and adapted to cut the paper in the direction of its width; of a second knife disposed at an angle to the first named knife and adjustably connected thereto whereby it may be moved laterally, substantially as and 90 for the purpose set forth.

5. In a paper serving apparatus, the combination with a frame adapted to mount or support a roll of paper and a knife extending in 95 the direction of the length of the frame and the paper roll and adapted to cut the paper in the direction of its width; of a slide block, a tongue and groove connection between said slide block and the knife, and a second knife carried by the slide block, substantially as 100 and for the purpose set forth.

6. In a paper serving apparatus, the combination with a frame adapted to mount or support a roll of paper and a knife extending in 105 the direction of the length of the frame and the paper roll and adapted to cut the paper in the direction of its width; of a slide block, a tongue and groove connection between said slide block and the knife, and a second knife pivotally connected to the slide block, substantially as 110 and for the purpose set forth.

7. In a paper serving apparatus, the combination with a frame adapted to mount or support a roll of paper, and a knife connected with the frame and disposed in the direction 115 of the length of the frame and paper roll and having a tongue upon its outer side; of a slide block having a groove to engage the tongue of the knife, and a second knife pivotally connected to the slide block, substantially as and 120 for the purpose set forth.

In testimony whereof I affix my signature in presence of two witnesses.

THOMAS GASKINS.
